[57] CLAIM

The ornamental design for a combined pump and nozzle for sprayer, substantially as shown.

DESCRIPTION

FIG. 1 is a perspective view taken from the top, front and right side of a combined pump and nozzle for sprayer showing my new design;

FIG. 2 is a front elevational view thereof;

FIG. 3 is a right side elevational view thereof; the left side being a mirror image of the right side shown;

FIG. 4 is a rear elevational view thereof;

FIG. 5 is a bottom plan view thereof; and

FIG. 6 is a top plan view thereof.

FIG. 2

FIG. 1
